UNITED STATES PATENT OFFICE.

ALWIN KOST, OF SEATTLE, WASHINGTON.

PHYSICAL-CULTURE APPARATUS.

1,257,957.

Specification of Letters Patent. Patented Feb. 26, 1918.

Application filed July 11, 1916. Serial No. 109,804.

To all whom it may concern:

Be it known that I, ALWIN KOST, a citizen of Germany, residing at Seattle, in the county of King and State of Washington, have invented a new and useful Improvement in Physical-Culture Apparatus, of which the following is a specification.

This invention relates to improvements in physical culture apparatus and the object 10 of this improvement is to provide apparatus for imparting to the body a correlated series of muscular exercise and at the same time thoroughly massaging the trunk of the user during the process of the exercise.

15 The invention consists in the novel construction, adaptation and combination of parts of a physical culture apparatus as will be more clearly described in the following specification, illustrated in the accompanying drawings and finally pointed out in the appended claim.

In the accompanying drawings Figure 1 is a view in side elevation of my apparatus as it may appear when in use, a portion being broken away to reveal inferior construction; Fig. 2 is a plan view of a massage cradle embodied in the invention; Fig. 3 is a view in cross section on broken line 3, 3 of Fig. 2; Fig. 4 is a view in cross section on broken line 4, 4 of Fig. 2; Fig. 5 is an enlarged view in cross section of one of the balls used on the massage cradle and Fig. 6 is a somewhat diagrammatic view illustrating the means used to electrify the massage cradle.

Referring to the drawings throughout which like reference numerals indicate like parts, the numeral 8 indicates a fixedly secured upright post, preferably of rectangular cross section, that forms a support for my physical culture apparatus, and 9 is a bracket slidably mounted on the post 8 and held in adjusted vertical position by a set screw 10 or equivalent device. The bracket 9 projects outwardly from the post 8 and has the upper end of a flexible cable 11 secured thereto, the lower end of the cable 11 being connected with a cross bar 12 that serves as a hand hold and may be grasped 45 by the user as shown in Fig. 1 to permit the body to be stretched to its full length, and to further permit a twisting or wriggling motion to be imparted to the body.

Below the bracket 9 is another slidably bracket 13, held in adjusted position by a set screw 14 and recessed as at 15 for the

reception of a pipe or tube 16 within which is telescoped a plunger 17 that is articulated by a pivot 18 with the central portion of frame bars 19 that support a massage 60 cradle 20. The tube 16 is adjustable longitudinally of the recess 15 and is held in any desired position by a set screw 21.

A compression spring 22 is interposed between the end of the tube 16 and the inner 65 end of the plunger 17 to form a yielding or elastic support for the cradle 20.

The massage cradle 20 is provided with a plurality of vertically arranged spindles 23 upon which are mounted balls 24 preferably of rubber or of other like relatively soft material that are adapted to engage with the body of a person and massage the 70 stomach portions thereof, while the exercise is being taken.

75 Each of the balls 24 is provided with a plurality of fine contact wires 25, extending radially thereof and formed like helical springs, such wires making contact at their inner ends with the spindles 23 and terminating at their outer ends in such manner that they will make contact with the body of the operator but will not present sharp ends to scratch the body. This may be accomplished by doubling the ends of the 80 wires backwardly into the ball, as shown at 26 in Fig. 5.

The cradle 20 is preferably electrified as by a battery 27 connected thereto by circuit wires 28 wherein is provided a switch 29.

90 The top and bottom sides respectively of the cradle 20 are connected with the tube 16 by helical tension springs 30 that work in opposition and in balanced relation to the spring 22 and admit of a vertical tilting movement of the cradle during the operation of massaging the abdominal portions of the body.

95 31 are arms that are articulated with the cradle supports by pivots 32 and engaged 100 by compression springs 33 whereby they are urged inwardly and made to serve as guides to prevent the body from rolling off of the cradle. The springs 33 are preferably made fast to the arms 31 as by soldering and the 105 pivots 32 are easily removable so that the arms 31 may be entirely disconnected from the cradle and the cradle turned quarter way around by loosening the set screw 21 and turning the tube 16 in the recess 15.

110 When the table is turned quarter way around as above described, it will be rigidly

supported in a vertical plane, and the spindles 23 will be horizontal. In this way it is better adapted for massaging the back by reversing the position of the body from that shown in Fig. 1, and moving the body up and down over the cradle 20.

When in use the bracket 9 is adjusted vertically so that the user by rising slightly on his toes and stretching to full length can just reach the hand hold 12, and the cradle 20 is adjusted vertically so that it will engage the stomach of the user when he is in the above described position. The exercise is taken by raising and lowering the body and twisting from side to side the balls 24 rolling on the spindles 23, and thoroughly massaging the abdominal portions as the body is moved thereover. It will be noted in Fig. 1 that the cradle 20 projects outwardly from the support 8 farther than the hand hold 12 whereby the weight of the body when it is stretched to full length will cause a pressure of the abdomen against the cradle. This pressure may be regulated by adjusting the position of the tube 16 within recess 15.

The massaging of the abdomen while the muscles thereof are in a stretched or extended position is found extremely beneficial to the abdominal organs and the massaging of the abdominal portions of the back while the body is stretched at full length is particularly beneficial to the spinal column for the reason that it tends to loosen up and adjust

the cartilaginous cushions between adjacent vertebra, and if persevered in, will cause a thickening of such cushions in places where the vertebra have grown too closely together and caused a pressure on the nerves that issue from between such vertebra.

The current of electricity may be regulated to suit the individual and by reason of its being administered simultaneously with the massaging of the abdominal regions is particularly beneficial.

What I claim and desire to protect by Letters Patent is:

Apparatus of the class described comprising a support having hand holds associated with the top portion thereof, a vertically adjustable bracket disposed below said hand holds said bracket having a recess formed therein, a tube adjustable longitudinally of said recess, a compression spring in said tube, a plunger movable in said tube and working against said spring, a massage cradle pivoted on said plunger and tiltable in one plane only, tension springs connected with the top and bottom portions of said cradle, spindles extending crosswise of said cradle, balls on said spindles, means for electrifying said balls and spring pressed arms for sustaining a body against lateral displacement on said cradle.

ALWIN KOST.
